UNITED STATES PATENT OFFICE.

MADS M. LARSEN, OF COLTON, CALIFORNIA.

THREAD HOLDER AND PINCUSHION.

Application filed January 6, 1925. Serial No. 812.

To all whom it may concern:

Be it known that I, MADS M. LARSEN, a citizen of the United States, residing at Colton, in the county of San Bernardino and State of California, have invented new and useful Improvements in Thread Holders and Pincushions, of which the following is a specification.

The object of this invention is to provide 10 a holder for spools of thread constructed in such a manner that a plurality of spools of thread is carried in compartments of an axially mounted magazine, each compartment having openings covered with a transparent 15 material so that the different colors of the thread on the spools therein may be seen.

Another object of this invention is to provide a thread holder in the form of a magazine adapted to receive a plurality of spools 20 of thread in individual compartments, rotatably mounted on spindles, the compartments having openings through which the thread may pass as it is being used.

A further object of this invention is to 25 provide a thread holder and pin cushion, the pin cushion being mounted on a frame supporting a magazine adapted to hold a plurality of spools of thread.

With the foregoing and other objects in 30 view which will be made manifest in the following detailed description and pointed out in the appended claims, reference is had to the accompanying drawings for an illustrative embodiment of the invention, wherein:

35 Figure 1 is a side elevation of the thread holder and pin cushion;

Fig. 2 is an end elevation looking in the direction of the arrow 2 in Fig. 1;

Fig. 3 is a vertical section taken on the 40 line 3—3 of Fig. 2;

Fig. 4 is a transverse section taken on the line 4—4 of Fig. 1; and

Fig. 5 is a side elevation of one of the 45 spool holding spindles.

Referring to the accompanying drawings wherein similar reference characters designate similar parts throughout, 10 designates a base upon which is mounted standards 11 secured to the base by screws 12 or other suitable fastening means. The standards 11 have openings 13 in alignment which act as bearings for stud shafts 14 secured to end plates 15 and 15^a of a spool holding magazine, generally designated at 16. Each of 50 the stud shafts 14 have a flange 14^a and are held in place by a nut or collar 14^b. The

spool holding magazine is composed of a plurality of cylindrical compartments 17 secured to the end plates 15 and 15^a, each compartment having an oblong opening 18 60 adjacent an opening 19, having an annular end portion 20 and a slotted portion 21 in registration with a radial opening 22 formed in the end plate 15.

Each of the compartments are partially 65 covered by a strip 24 of transparent material, such as celluloid, these strips of celluloid being inserted between the extremities of arcuate plates 25 secured to the end plates 15 and 15^a. Each of the strips of celluloid 70 have openings 26 corresponding to the opening 19. Spools of thread indicated at 27 are rotatably mounted on spindles 28. Each of the spindles has a handle portion 29, a flange 30, and a threaded portion 31 adapted 75 to be screwed into an opening 32 in an annular lug 33 formed on the end plate 15. When it is desired to fill the magazine, the spindles are removed and the spools of 80 thread are mounted thereon. A short length of thread is unwound from the spool and the spindles carrying the spools of thread are then inserted into the cylindrical compartments, the length of thread passing 85 through the openings 22 and slot 21. The spindle is then screwed into the opening 32 until the flange engages the side plate 15. The projecting length of thread may then be wrapped around ears 34 formed on the 90 side plate 15.

A plate 35 having upturned ends 36 is mounted between the upper ends of the standards 11. The plate 35 together with the end plates 11 form a receptacle adapted 95 to receive a pin cushion 37. The pin cushion 37 may be of any suitable construction, such as a layer of fabric 38 enclosing suitable stuffing 39 mounted on a base 40 within the receptacle and held in place by tacks 41.

From the construction it will be seen that 100 the spools of thread in the compartment of the magazine are protected from dust and dirt by the transparent strip of material covering the oblong opening 18, and that the color of the thread may be observed 105 without removing the spools.

When it is desired to use the thread on one of the spools, the magazine is rotated until the spool required is in a convenient position, and the length of the thread projecting on the ear 34 is then unwound. As 110 the thread is used, the spool will freely ro-

tate on the spindle and pass through the opening 19.

It will be particularly noted that as the thread is used, the spools remain in the magazine, thus eliminating the annoyance and inconvenience caused by the spools dropping on the floor and rolling under furniture and the thread thereon becoming tangled. The combination of the pin 10 cushion with the magazine is very desirable as pins and needles are always used in connection with thread.

It will be understood that various changes may be made in the detail of construction 15 without departing from the spirit or scope of the invention as defined by the appended claims.

I claim:

1. A holder for spools of thread, comprising in combination a thread compartment formed substantially cylindrical with a closed wall at one end and an opening at the other through which spools may be inserted, a spool holding spindle having a 20 spindle rod, a handle at one end of the rod, a flange at the handle and adapted to close the open end of the cylinder and means to secure the other end of the spindle rod to the closed end of the cylinder.
2. A holder for spools of thread, comprising a base, standards mounted on the base, a magazine having a plurality of cylindrical compartments open at one end through which spools may be inserted, a spool holding 25 spindle for each compartment comprising a spindle rod, a handle having a flange to close the open end of the cylinder and means to secure the other end of the spindle rod in the inner end of the cylinder.
3. In a device of the character described,

a magazine comprising a plurality of cylinders, each cylinder having an opening therein, a second opening adjacent said first opening, a pair of side plates secured to and closing the ends of said cylinders, and strips of transparent material secured to and partially covering each cylinder and having an opening registering with the second opening in each cylinder.

4. A holder for spools of thread comprising in combination a pair of circular plates, an annular row of cylindrical compartments attached to said plates and closed at one end by one of the plates and having free openings through the other plate for the insertion of spools, a spool holding spindle for each compartment having a spindle rod with a handle on the end of the rod, a flange plate adjacent the handle and screw threaded to the plate forming the closure of the cylindrical compartments and an opening in each compartment for the withdrawal of thread.

5. A holder for spools of thread as claimed in claim 4, having in addition radial grooves in the circular plate having the open ends of the compartments in alignment with a groove in the wall of the compartment through which the free end of the thread may be inserted and removed.

6. A holder for spools of thread as claimed in claim 4, having in addition a slot through the walls of each compartment, a sheet of transparent material secured to each cylinder and having an opening therethrough for the insertion and removal of thread.

In testimony whereof I have signed my name to this specification.

MADS M. LARSEN.
